CONSTRUCTION OF GASOMETER ROOF TANKS

Ernest H. Staber, Manhasset, N. Y., assignor to
Socony-Vacuum Oil Company, Incorporated,
New York, N. Y., a corporation of New York

Application January 26, 1934, Serial No. 708,351

2 Claims. (Cl. 220—85)

This invention is directed to improvements in storage tanks for volatile liquids, and more particularly, is directed to improvements in tanks having a gasometer type roof.

5 The gasometer roof tank is a tank in which the roof has a depending skirt which dips into a trough extending around the circumference of the tank wall proper, either inside or outside, at the top. This trough or well is filled with liquid, and the tank roof is free to rise and sink in accordance with the vapor pressure below. The application of excess pressure and vacuum is avoided by the use of proper relief valves.

10 One of the difficulties experienced with gasometer roof tanks has been the escape of condensed liquid through the circumferential well, which has taken place as follows: The metallic roof, in contact with cool air on the outside (at night, etc.) and with hydrocarbon vapors on the inside, causes these vapors to condense on the under side of the roof. Due to the pitch of the roof, they run to the edge, drip into the well and eventually fill it on the inside.

15 25 Other difficulties had with these roofs have been the provision of proper gauging means whereby the measurement of the contents of the tank might be effected, without allowing the escape of vapors or without attempting to find a time when the tank was not under pressure or vacuum and gauging at that time.

20 In addition, pressure and vacuum relief valves of the types commonly supplied have not been properly applicable to the problems presented by gasometer roof tanks.

25 The object of this invention has been to devise a gasometer roof tank in which the loss of stored fluid by escape through the dip ring seal has been prevented. A further object has 30 been the provision of reliable and easily operated gauging means, and the provision of reliable pressure and vacuum relief valves. Additionally, other objects and advantages have been attained, as may hereinafter appear.

35 45 The various objects and advantages are obtained by means of the designs set forth in this specification and shown in the drawings attached to and made a part hereof.

In these drawings,

50 Figure 1 is a section through the dip ring seal, Figure 2 is a section of a portion of the dip ring,

55 Figure 3 is a diagram showing the action of the dip ring seal when venting,

Figure 4 is a diagram showing conditions when dip ring is at its low point,

Figure 5 is a diagrammatic section showing a gauge well,

Figure 6 is a diagram showing relief valves, 5

Figure 7 is a section through one relief valve chamber.

Referring now to the manner in which the loss of condensate collected in the dip ring seal is avoided, the method of operation is based on 10 the following:

15 Being lighter than and not soluble in the liquid within the trough, the condensate will collect and float on the surface of said liquid and in doing so, a pressure equilibrium on the two sides of the dip ring will always be maintained as shown by the following formula:

20 Hydrostatic liquid pressure on outside of dip ring—hydrostatic pressure of sealing liquid and superimposed gasoline on inside of dip ring, 20 plus the existing vapor pressure within the tank.

25 As the gasoline condensate accumulates, the plane where the sealing liquid and gasoline meet lowers, and the upper surface of the gasoline rises.

30 The pressure required to lift the gasometer tank roof determines the venting position of the lower edge of the dip ring. For example, if water is used as the sealing liquid and a pressure equivalent to that of a column of water three 35 inches in height is required to raise the roof, the tank will vent by vapor bubbling through the water underneath the dip ring when the lower edge of said dip ring has risen to within three inches of the surface of the water on the outside 40 of this dip ring. If gasoline has accumulated on the inside of this dip ring below this point, the instant the lower edge of the dip ring is rising, passes the plane where water and gasoline 45 meet, gasoline will flow underneath the dip ring to the outside surface of the sealing liquid where it readily evaporates. In addition to losses incurred through the evaporation of this released condensate, fire risks and venting are materially increased.

50 To stop this gasoline from escaping in this manner is one of the major objects of this invention, the several objects of the several pertinent portions of the invention being prevention of escape of gasoline to the outside portion of the well, minimizing of drip accumulations in the inner portion of the well, and returning such drip as does accumulate to the

body of the tank, and such other objects and advantages as may hereinafter be shown.

These objects have been accomplished largely by taking advantage of the relative specific 5 gravities of water and of gasoline. In order to better understand the manner in which this has been done and the means by which it is accomplished, reference is made to Figures 1 to 4 inclusive.

10 In Figure 1, 1 is the tank wall bounded circumferentially inside at the top by stiffener member 14. Attached to the exterior of the tank shell is a circumferential well composed of horizontal plate 3 and vertical plate 4, which in 15 turn has a girder member 5. At various points around the circumference of the tank on the inside of plate 4, there are installed sealing liquid overflow boxes 6, from which said liquid is led away by pipes 7. Depending into the circumferential well is the dip ring sheet 8 attached to the roof 9. At intervals on the interior of the dip ring sheet are placed vent boxes 10. I have made these vent boxes of a trough or channel-shaped section of iron turned so that its legs 20 are in contact with dip ring 8, and have welded it to the dip ring, forming a vertical box of small liquid capacity, but of ample dimension for the passage of gases. I have closed the bottom of this box by a welded plate 11, but this 25 closing is not essential, and have formed hole 12 in plate 8 so that gases escaping may pass down through the interior of member 10 and through hole 12. On the interior of roof 9, at a point near the outer edge thereof, I have placed 30 a light angle iron 13, the purpose of this angle iron being to form a drip point for the condensate collected on the interior of the tank roof inside of the circle formed by 13. In this manner I am enabled to keep the major portion of 35 the condensate from getting into the circumferential well, only that condensate formed between 13 and 8 being able to drop into the well.

Figure 2 is a section of a portion of dip ring 8 showing channel 10 and hole 12.

40 The objects of this vent box are as follows:

1. Stop vapor escaping by bubbling underneath dip ring.
2. Force vapor to escape by passing through vent box 10, and hole 12 through which condensate cannot escape. This venting will take place when the roof has risen to a point where the liquid pressure above said hole is equal to the pressure required to raise the roof.

3. Use the bottom of dip ring as trap to prevent 45 the escape of condensate by limiting the height to which dip ring can rise. This is accomplished by locating vent hole 12, a desired distance above bottom edge of dip ring as determined hereinafter mathematically.

4. Automatically force gasoline condensate which collects on the surface of the sealing liquid on the inside of dip ring, back into the tank by flowing over the top of the tank or through a properly located overflow hole, notch 50 or box. This is accomplished by taking advantage of the difference in specific gravity of the condensate and the sealing liquid.

To illustrate, the following assumptions are made, from which the vertical location of hole 55 12 is determined algebraically:

Let a =vertical distance in inches between top of tank at 14 and top of overflow box 6.

Let p =pressure in inches of water required to raise roof.

75 Let s =specific gravity of condensate.

Let h =maximum depth in inches to which condensate can accumulate on inner side of dip ring.

Let w =distance in inches between bottom edge of dip ring and top of overflow box 6 (sealing liquid surface) when roof is in venting position.

Let b =vertical distance between bottom edge of dip ring and vent hole 12.

Let sealing liquid be water.

In order to have static equilibrium, pressures 10 on the inside of dip ring must equal those on the outside, therefore

$$w=p+sh$$

$$w \text{ also } = h - a, \quad 15$$

Therefore

$$h - a = p + sh; h = \frac{p + a}{1 - s}$$

$$b = \frac{p + a}{1 - s} - (a + p) \quad 20$$

If the condensate is gasoline which has a specific gravity of 0.75, if $p=3''$ of water, which is approximately what is found in practice and $a=2\frac{1}{2}''$, then

$$h = \frac{3 + 2\frac{1}{2}}{1 - .75} = 22'' \quad 25$$

and

$$b = 16\frac{1}{2}$$

h and b can also be determined for any pressures below that required to lift the roof (which is the maximum) but for all such pressures both h and b will have lower values making such calculations unnecessary.

Experience has shown that the time which elapses between maximum and minimum vapor pressures within the tank are of short duration, during which period very little condensate can collect in the water seal, particularly if roof is equipped with drip angle. As a drop in pressure 35 (p) reduces the depth of accumulated condensate, any condensate which accumulates while the roof is in a raised position gradually reduces as the pressure drops and reaches a minimum when the vacuum valve opens to admit air. 40 These vacuum valves are usually designed to open when pressure within the tank is $1\frac{1}{2}''$ of water below that of the outside atmosphere. If this value of p is used in place of $3''$ in the above example, then

$$h = \frac{-1\frac{1}{2} + 2\frac{1}{2}}{1 - .75} = 4''$$

Thus the minimum value for h is 4" and the maximum, 22". Since the period which elapses between minimum and maximum pressures is of short duration, during which time very little condensate can accumulate, in practice it is found unnecessary to sacrifice $16\frac{1}{2}''$ of the lift by placing the vent hole $16\frac{1}{2}''$ from bottom edge of dip ring. It has been found that it is practical to reduce this distance to 6".

In order to prevent sealing liquid from flowing over the top of the tank into the gasoline, the distance "a" is made considerably greater than the vacuum in inches of water at which the breathing valve admits air.

The gauging of the contents of a tank of this type calls for certain precautions, because not only must the escape of gas while gauging be prevented, but the pressure or vacuum obtaining within the tank at the time of gauging will make certain alterations in the level of the contents which must be properly measured and taken into account. I have accomplished this 75

gauging by means of the device set forth diagrammatically in Figure 5, wherein, as before, 1 is the shell of the tank, 3 and 4 form the liquid seal around the upper edge of the shell, 8 is the dip ring at the edge of the roof, and 9 is the roof. At some point within the tank I have erected a vertical pipe 15, terminating at or near the bottom of the tank and closed on the bottom by a plate 16. In small tanks, or in tanks arranged so that the roof rotates as it rises, this pipe should be at the center. In other tanks, a location near the side wall is preferred. In the lower portion of pipe 15, for a distance of say 18 inches or two feet, I have perforated the pipe with a plurality of small holes 17, the arrangement and total area of these holes being such that the liquid within the pipe is always in free communication with the liquid outside of the pipe and the total area being sufficiently small so that momentary surges in the exterior liquid, due to pumping, sudden pressure changes, and the like, are not communicated to the interior of the pipe in the form of surges. Around the top end of this pipe 15 at a level near that 25 of the seal on the outside periphery of the tank wall, I have provided an interior seal composed of a pipe 18, considerably larger in diameter than pipe 15, which is placed around pipe 15 and secured thereto by plate 19, which forms the bottom 30 of an annular liquid retaining space concentric with and exterior to pipe 15. I connect this liquid space to the liquid in the exterior seal by pipe 20, through which liquid may flow freely. Inside of the seal formed by pipe 18, and exterior 35 to the pipe 15, is a pipe 21 depending from and supported by the roof 9. I have thus set up at this point a trap for vapor of the same nature as that on the tank wall, with the following exception. The vertical length of pipe 18 is greater 40 than the vertical depth of the exterior trap, and the pipe 21 extends into the liquid in seal 18 to a greater depth than does the dip ring 8 in the exterior seal; consequently, any venting of vapors will occur at the exterior trap rather than 45 in the gauge well. The exterior portion of the pipe 21 is closed by a hatch 22 of any convenient form, preferably with a protecting lid. This lid should not be vapor tight, but should be 50 vented to the atmosphere to protect against vacuum and pressure. In gauging the tank, a pole or tape 23 is inserted through this gauge hatch 22 and into the interior pipe 15 until it is stopped by touching bottom, after which it is withdrawn and the depth to which it is wetted is noted, this 55 giving the height of the level 24. This level 24 is not the same as the actual level 25 of the liquid within the tank, the difference being that amount 26 due to the variation between internal and external pressure, an amount which 60 may be either plus or minus. To observe the amount of this difference 26, a quantity of the liquid from within the tank is withdrawn through the gauge hatch and placed in the manometer 27 which is arranged upon the roof at a point 65 convenient to the gauge hatch. In this manometer the difference 26 is reproduced, and as the liquid in the manometer is of exactly the same nature as that in the tank, no corrections for specific gravity and the like need be made. The 70 difference 26 observed in the manometer is applied to the level 24 observed by means of the gauge pole and the correct level 25 thus determined, and by reference to a computed table of tank capacity, the gallonage at this level is determined.

To protect this tank against vacuum and against pressures which might not be properly relieved due to failure of operation of the roof, or to other causes, I make use of protective vacuum and pressure relief valves which are set forth 5 diagrammatically in Figure 6. In this figure, 28 and 29 are valve chambers cylindrical in cross section, set up adjacent the top of the tank wall in a convenient operating location, and at a height such that they may communicate with 10 each other through connection 30 and with the dip ring trap on the tank wall through connection 31, thereby being filled with the same liquid as is used in the dip ring and being subjected automatically to the same conditions of dip ring 15 level, etc. Chamber 28 is used for the release of pressure within the tank and is equipped with a vapor inlet 32 opening centrally into the bottom of the chamber 28. This vapor inlet is surrounded by a circular pipe 33 extending upward 20 within chamber 28 to a level somewhat greater than the level of the water overflow on the dip ring trap. Over this central pipe 33 and surrounding it, there is placed a gasometer float 34 which extends in its normal position into the 25 liquid in the vessel 28 to a depth of say 22 to 24 inches. This gasometer float 34 is made of a light weight metal such as aluminum and its weight is adjusted by machining so that it will rise and vent at the proper pressure. In other 30 words, if the dip ring vent is designed to operate at say 3 inches of water and it is decided that the safety vent shall operate at five inches of water, the weight of the gasometer float 34 is such that a pressure of five inches of water 35 exerted upon its area will lift it, allowing gas to escape under the bottom of its skirt. In the design of valves for use on tanks working at high pressure, heavier metals, such as steel might be used. The skirt of this gasometer float 34 is 40 provided with a plurality of ribs 35 which serve to guide it within chamber 28. Chamber 28 is open to the atmosphere through an orifice 37 at its top, and is of sufficient height to handle the full rise of gasometer float 34 and still retain 45 it in position to properly return to its seat when through venting. Chamber 28 is connected to the pressure space within the tank by inlet 32 previously mentioned, and by pipe 38 which terminates within the tank at a point well up in the 50 vapor space near the roof. For the relief of vacuum, a similar chamber 29, equipped with a similar interior pipe 39 and a similar gasometer float 40, is used, with the difference that in this case the port 41 at the bottom of chamber 29 55 is open to the atmosphere, and the top of the chamber 29 is closed to the atmosphere and in communication with vent line 38. The gasometer float 40 has similar ribs 36 and in this case is machined so that its weight enables it to act 60 at the desired vacuum, which may for example be 1 1/2" of water, so that when a vacuum greater than this amount exists within the tank, the gasometer float 40 will rise and air admitted through 41 will pass upward through pipe 39, the 65 gasometer float will rise to operating position, and the air will then pass downward around gasometer float 40, into chamber 29, and through pipe 38 into the vapor space of the tank. It is noted that this type of construction provides an 70 unusually long liquid seal. Any of the usual devices for protecting a vent line against the striking back of flame may be inserted at any point in the line 38, or if desired, may be applied to orifices 37 and 41. Figure 7 shows a section 75

through chamber 28 looking downwardly, and sets forth in greater detail the location of the ribs 36 upon the side of the gasometer float 34 and the annular relationship of orifice pipe 33 and gasometer float 34.

Certain advantages of this form of relief valve will at once be apparent. In the past, relief valves of this type have been made so that they vented with a comparatively short rise and the rapidity with which they acted resulted in a considerable blowing of the sealing liquid. Many liquids have been used as seals ranging from mercury through glycerine to water and light petroleum fractions. None of them have been eminently successful, yet a liquid seal valve is so much more desirable than one sealed by mechanical seating of the valve, that the type has persisted in spite of its defects. These disadvantages I have avoided in several ways: First, I have eliminated the most frequently performed function, namely, that of pressure venting for ordinary rises, and do not call upon the vent valve to perform this routine venting, and reserve for it only the duty of emergency relief, which can only occur when excessive binding takes place between roof guides and rolls, (which condition should be immediately corrected). Secondly, I have provided a vent valve on the gasometer principle, having a depth comparatively great in relation to the necessary movement of the valve. For instance, in the pressure valve of the example cited, I have a 22 inch depth of seal to handle a five inch pressure variation, and consequently considerable blowing may take place before the liquid has been reduced to a depth where it will fail to seal. Third, I may so place these liquid seals that they are always in communication with and in a position to be replenished by the enormously larger reservoir

of liquid in the dip ring seal, thereby assuring an ample supply of liquid in seals of valves.

I claim:

1. In a gasometer roof tank for storage of volatile liquids having a circumferential liquid trap located adjacent the top of the tank shell and a dip skirt on the roof depending thereinto, a plurality of vent boxes located upon the interior of the dip skirt, communicating at their top ends with the vapor space in the tank, each extending to near the bottom of the dip ring and communicating with the liquid space on the outside of said dip ring by an aperture whereby, when venting, the tank gases preferentially may pass into the upper end of the vent box, down through said box, and out through said aperture to a region of lower pressure.

2. In a gasometer roof storage tank for volatile liquids wherein a dip skirt depends from the roof into a circumferential liquid seal well, a liquid in such seal which is not miscible with condensate from the vapors within the tank and of greater specific gravity than such condensate, a plurality of apertures in said dip skirt adjacent the bottom edge thereof, passages communicating between said apertures and the vapor space within the tank, an overflow to limit the rise of seal liquid in the space external to the dip skirt, said overflow being not less than two and one-half inches below the top of the tank wall which defines the inner side of the seal chamber, the apertures being not more than sixteen inches nor less than four inches distant from the bottom edge of the dip skirt, and the weight of the roof being not less than about five pounds per square foot of projected area exposed to the pressure of the vapors within the tank.

ERNEST H. STABER.
